UNITED STATES PATENT OFFICE

143,324

DESIGN FOR A RAILWAY CAR

George A. Jergenson, Detroit, Mich., assignor to
General Motors Corporation, Detroit, Mich., a
corporation of Delaware

Application April 30, 1945, Serial No. 119,314

Term of patent 14 years

(Cl. D66—1)

To all whom it may concern:

Be it known that I, George A. Jergenson, a citizen of the United States and a resident of Detroit, county of Wayne, State of Michigan, have invented a new, original, and ornamental Design for a Railway Car, of which the following is a specification, reference being made to the accompanying drawings forming a part thereof.

In the drawings:

Fig. 1 is a side elevational view of a railway car showing my design.

Fig. 2 is an elevational view, showing the side of the car opposite to that shown in Fig. 1.

Fig. 3 is a top plan view of the car.

Fig. 4 represents a diagrammatic outline of a sectional view, taken on the line 4—4 of Fig. 1.

Fig. 5 is a sectional view, taken along the longi-

tudinal center line of the car, showing the interior of the car.

Fig. 6 is a sectional view, taken on the line 6—6 of Fig. 5.

Fig. 7 is a sectional view, taken on the line 7—7 of Fig. 5.

Fig. 8 is a sectional view, taken on the line 8—8 of Fig. 5.

Fig. 9 is a sectional view, taken on the line 9—9 of Fig. 6.

The appearance of the end portions of the railway car is conventional.

I claim:

The ornamental design for a railway car, substantially as shown and described.

GEORGE A. JERGENSON.
